US00D711848S

(12) **United States Design Patent**
Liu

(10) **Patent No.:** **US D711,848 S**
(45) **Date of Patent:** **** Aug. 26, 2014**

(54) **TRANSMITTER**

(71) Applicant: **Shenzhen Aetertek Technology Co., Ltd.**, Shenzhen (CN)

(72) Inventor: **Yunbing Liu**, Shenzhen (CN)

(73) Assignee: **Shenzhen Aetertek Technology Co., Ltd.**, Shenzhen (CN)

(**) Term: **14 Years**

(21) Appl. No.: **29/460,561**

(22) Filed: **Jul. 12, 2013**

(51) LOC (10) Cl. **14-03**

(52) U.S. Cl.

USPC **D14/155**

(58) **Field of Classification Search**

(57) **CLAIM**

The ornamental design for a transmitter, as shown and described.

DESCRIPTION

FIG. 1 is a front view of a transmitter of my new design;
FIG. 2 is a back view of the transmitter thereof;
FIG. 3 is a left view of the transmitter thereof;
FIG. 4 is a right view of the transmitter thereof;
FIG. 5 is a top view of the transmitter thereof;
FIG. 6 is a bottom view of the transmitter thereof;
FIG. 7 is a first front perspective view of the transmitter thereof;
FIG. 8 is a second front perspective view of the transmitter thereof; and,
FIG. 9 is a back perspective view of the transmitter thereof.
